UNITED STATES PATENT OFFICE

2,161,021

COMBUSTION APPARATUS

Martin De Lin, Holland, Mich., assignor to Holland Furnace Company, Holland, Mich., a corporation of Michigan

Application April 5, 1937, Serial No. 134,984

4 Claims. (Cl. 158—1)

This invention relates to combustion apparatus, and more particularly to improvements in the construction of combustion chambers and the arrangement of same with respect to a heat exchanger.

The principal object of this invention is to provide for an improved transfer of heat from the combustion chamber to the medium to be heated. This object is attained in part by positioning the combustion chamber within a heat exchanger in spaced relation thereto, the combustion chamber being formed to provide for the circulation of the products of combustion substantially uniformly throughout the heat exchanger. Specifically, the combustion chamber is formed with outlet openings for the discharge of the products of combustion in both the lower and upper portions thereof.

Realization of the foregoing object is attained, in part also, by positioning the heat exchanger within a casing through which the medium to be heated passes in such manner that substantially the entire exterior surface of the heat exchanger is exposed to the medium to be heated.

Various other objects more or less incidental and ancillary to the foregoing will appear from the following description, when read in connection with the accompanying drawing, wherein—

Figure 1 is a side view in elevation of a combustion apparatus embodying the present invention with parts broken away to show the interior construction thereof;

Figure 2 is a sectional view taken on substantially the line 2—2 of Figure 1; and

Figure 3 is a perspective view of the combustion chamber shown in Figures 1 and 2.

The combustion apparatus illustrated in the accompanying drawing includes a combustion chamber 10, a heat exchanger 11 surrounding the combustion chamber and supported by a supporting frame 12, an inner casing 13 surrounding the heat exchanger and arranged in spaced relation thereto, an outer casing 14 surrounding the inner casing and arranged in spaced relation thereto, a burner 15 for supplying a mixture of fuel and air to the combustion chamber 10, and an auxiliary casing 16 enclosing the burner 15.

The outer casing 14 is provided with a pair of inlet openings 16. An opening is formed in the bottom wall of the inner casing 13 to provide communication between the inner and outer casings. Inner casing 13 is also provided with an outlet opening 17 in the top thereof. The medium to be heated, in this case, air, may be cir-

culated through the apparatus by a conventional form of circulating pump, not shown.

The heat exchanger 11 is formed to provide an expansion chamber 11a at the forward end thereof, and an economizer chamber 11b at the other end. Economizer chamber 11b is provided with a pair of vertically spaced openings 18 with which are associated the outlet flues 19 and 20. The entire heat exchanger 11 is made up of a plurality of sectional compartments 21 and 22. The compartments 21 form the expansion chamber. The compartments 22 form the economizer chamber. These sectional compartments are clamped together by means of rods 23 extending through aligned openings in external ears. The sectional compartments are formed to provide a continuous horizontal passageway throughout the heat exchanger 11.

The details of construction of the combustion chamber 10 are shown in Figure 3. As there shown, the combustion chamber is of generally rectangular shape, having vertical side walls 24, end walls 25, and a horizontal bottom wall 26. Inclined wall sections 27 are interposed between the lower edges of the side walls and the adjacent edges of the bottom wall. Each of these inclined wall sections is provided with an opening 28 throughout its entire length. The side walls terminate at their upper extremities in oppositely inclined wall sections 29 which tend to restrict the opening in the top of the combustion chamber. An inlet opening 30 is formed in one of the end walls 25 of the combustion chamber.

The front end (right hand side of Figure 1) of the heat exchanger 11 is closed by a removable plate 31. Plate 31 is provided with an opening 32, and combustion chamber 10 is secured to plate 31 with the opening 30 of the combustion chamber registering with the opening 32 in the plate. As clearly shown in Figures 1 and 2, combustion chamber 10 is supported within the expansion chamber 11a in spaced relation to the walls thereof.

A bracket 33 is secured to the outer side of plate 31, upon which burner 15 is supported. The burner is adapted to deliver a combustible mixture of fuel and air to the combustion chamber 10 through a conduit 34 which has one end connected to the burner 15 and the other end of which projects through aligned openings 30 and 32.

Burner 15 is here shown as a conventional gun type of oil burner which delivers a mixture of atomized fuel oil and air to the combustion chamber 10.

ber 10 under pressure. Oil and electrical current are supplied to the burner 15 in any conventional manner from sources not shown.

Combustion is initiated in combustion chamber 10. The flames resulting therefrom and the products thereof are discharged from the combustion chamber into expansion chamber 11a through the open top of combustion chamber 10 and the openings 27 in the lower portion thereof.

10 Due to the pressure created by the burner 15 and the location of the openings 27, the flames and products of combustion are discharged from the combustion chamber 10 in a manner to distribute them uniformly throughout the expansion chamber 11a. Contact between the products of combustion and substantially the entire inner surface, including the bottom, of expansion chamber 11, is thus assured.

From the expansion chamber 11a, the products of combustion pass into the economizer chamber 11b, and are then discharged to a chimney through exhaust flues 19 and 20. By providing upper and lower exhaust flues, the products of combustion are distributed vertically 25 in the heat exchanger 11 throughout their entire travel from the combustion chamber 10 to the exhaust flues 19 and 20.

As previously stated, substantially the entire exterior of the heat exchanger 11, including the 30 bottom thereof, is directly exposed to the medium to be heated. Thus, there is assured an efficient transfer of the heat of combustion to the heat exchanger and also from the heat exchanger to the medium to be heated.

35 The scope of the invention is indicated in the appended claims.

I claim:

1. A device of the character described comprising a hollow heat exchange body, a combustion chamber disposed within the heat exchange body in spaced relation to the walls thereof, the combustion chamber having an inlet opening and upper and lower outlet openings, the lower outlet openings being arranged to direct the products of combustion downwardly whereby the vertical walls of the heat exchange body are heated substantially uniformly throughout their vertical extent, and a burner associated with the inlet opening of the combustion chamber, said burner adapted to deliver a supply of fuel and air to the combustion chamber for combustion therein.

2. A device of the character described comprising a hollow heat exchange body provided with a horizontal passageway having vertical side walls and upper and lower exhaust flues at one end thereof, a combustion chamber disposed within the other end of the horizontal passageway in spaced relation to the walls thereof, the combustion chamber having an inlet opening in one end thereof and upper and lower outlet openings, the lower outlet openings being arranged 10 to direct the products of combustion downwardly whereby the vertical walls of the heat exchange body are heated substantially uniformly throughout their vertical extents, and fuel supply means associated with the inlet opening of the combustion chamber, said fuel supply means adapted to deliver a mixture of fuel and air to the combustion chamber for combustion therein.

3. A device of the character described comprising a hollow heat exchange body, a combustion chamber disposed within the heat exchange body in spaced relation to the inside walls thereof, the combustion chamber having an open top, vertical side walls, a horizontal bottom wall, and an inclined wall section between the lower edge 20 of each of the side walls and the adjacent edge of the bottom wall, said inclined section being provided with an elongated outlet opening, and means for delivering a supply of fuel and air to the combustion chamber for combustion there- 25 in.

4. A device of the character described including a casing for the circulation of a fluid to be heated, a hollow heat exchange body arranged within the casing in spaced relation to the casing 30 to permit circulation of the fluid completely around the heat exchange body, a combustion chamber positioned within the heat exchange body in spaced relation to the inside walls thereof, the combustion chamber having an inlet opening 40 and upper and lower outlet openings, the lower outlet openings being arranged to direct the products of combustion produced in the combustion chamber toward the bottom of the heat exchange body, and a burner associated with the inlet opening of the combustion chamber which is adapted to deliver a supply of fuel and air thereto for combustion therein.
